UNITED STATES PATENT OFFICE.

HENRY BREHMER, OF STAPLETON, ASSIGNOR TO DAVID WOLFE BRUCE, OF NEW YORK, N. Y.

DESIGN FOR TYPE.

SPECIFICATION forming part of Design No. 15,747, dated January 27, 1885.

Application filed December 13, 1884. Term of patent 14 years.

To all whom it may concern:

Be it known that I, HENRY BREHMER, (assignor to DAVID WOLFE BRUCE,) of Stapleton, county of Richmond, and State of New York, have invented a Design for a Font of Printing-Type, of which the following is a specification.

The nature of my design is clearly shown in the accompanying typographic impression, to which reference is made; and it consists of an unshaded letter of the class known as "Tuscan." The curved termination followed by the dot is found in the A, B, C, D, E, F, G, K, L, P, R, S, T, and Q, as shown. The faces 15 of the C D G O Q S are ornamented by a light curved line with dot termination, as shown. A similar ornamentation is found in the F, J, K, L, P, and R, as shown, formed, as it were, as a continuation of the termination proper.

The cross-line of the A is formed of the two 20 inclined lines intersected by a light line projecting downward. The cross-line of the H is the reverse of the cross-line of the A.

The character of the design is preserved in the lower-case, the punctuation-marks, the 25 numerals, and the dollar and pound-sterling marks, save that the faces of the punctuation-marks, the numerals, and the dollar and pound-sterling marks are not ornamented, as are the faces of the upper and lower case letters.

I claim as new—

The design for a font of printing-type, as shown and described.

HENRY BREHMER.

In presence of—

W. V. H. HICKS,
A. SIDNEY DOANE.
